US0D1055457S

(12) **United States Design Patent** (10) **Patent No.:** **US D1,055,457 S**
(45) **Date of Patent:** **** Dec. 31, 2024**

(54) **GRADUATION CAP HEADBAND**

(71) Applicant: **Tianjin Xiachan E-commerce Co., Ltd**, Tianjin (CN)

(72) Inventor: **Liguo Liang**, Tianjin (CN)

(73) Assignee: **Tianjin Xiachan E-commerce Co., Ltd**, Tianjin (CN)

(**) Term: **15 Years**

(21) Appl. No.: **29/945,743**

(22) Filed: **Jun. 5, 2024**

(51) LOC (14) Cl. **02-02**

(52) U.S. Cl.

USPC **D2/875; D28/41**

(58) **Field of Classification Search**

(57) **CLAIM**

The ornamental design for a graduation cap headband, as shown and described.

DESCRIPTION

FIG. 1 is a front perspective view of a graduation cap headband, showing my new design;
FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an exploded view thereof; and,

FIG. 10 is an enlarged detail view of area 10 in FIG. 2.

The broken lines define the bounds of the enlarged detail view of the graduation cap headband and form no part of the claimed design.

1 Claim, 10 Drawing Sheets
